UNITED STATES PATENT OFFICE.

JULIUS SCHACHT, OF NEW YORK, N. Y.

DESIGN FOR A BATHING-SUIT CARRIER.

Application filed January 26, 1922. Serial No. 368. Term of patent 7 years.

To all whom it may concern:

Be it known that I, JULIUS SCHACHT, a citizen of the United States, and a resident of the city of New York, borough of Manhattan, in the county and State of New York, have invented a new, original, and ornamental Design for a Bathing-Suit Carrier, of which the following is a specification, reference being had to the accompanying drawings, in which—

Fig. 2 is a side elevation thereof.

I claim:

The ornamental design for a bathing suit carrier, as shown.

JULIUS SCHACHT.
